UNITED STATES PATENT OFFICE.

HARRY J. DOOLITTLE AND OLIVER W. JOHNSON, OF CLEVELAND, OHIO; SAID JOHNSON
ASSIGNEE TO SAID DOOLITTLE.

CLOCK STRIKING MECHANISM.

1,142,943.

Specification of Letters Patent. Patented June 15, 1915.

Application filed July 21, 1913. Serial No. 760,298.

To all whom it may concern:

Be it known that we, HARRY J. DOOLITTLE and OLIVER W. JOHNSON, citizens of the United States, residing at Cleveland, in the 5 county of Cuyahoga and State of Ohio, have invented certain new and useful Improvements in Clock Striking Mechanisms, of which the following is a specification.

Our invention relates to new and useful 10 improvements in clocks and more particularly to the striking mechanism of clocks, the object of our invention being to provide a striking mechanism which will audibly indicate the hours and half hours in such a 15 manner that a person hearing the striking of the clock can always determine the time without looking at the same.

Heretofore it has been common practice 20 to make clocks which strike the half hours or half hours and quarter hours by one stroke of the same bell which strikes the hours. With clocks so constructed, it is impossible, when the clock is striking a quarter or half hour, to at all determine the time unless one has heard and remembered the hour 25 last struck. Even under such circumstances, it is impossible to determine whether it is quarter past that hour, half past that hour or quarter of the next following hour. A further difficulty met with in clocks of this 30 type is the fact that between the hours of twelve and two the striking of the clock, both the hours and fractions thereof, will be the same so that it is absolutely impossible 35 at such periods to determine the time. This latter difficulty has been overcome by constructing clocks in which the fractional parts of the hour are signaled by the striking of a bell of a different tone 40 from the bell sounding the hour. This does not however, do away with the difficulty of determining what particular half or quarter it is being struck, that is, for instance, whether it is half past four or half past five. 45 The object of our invention is to avoid this difficulty and construct a clock by means of which it will be possible to determine the exact time upon hearing the clock strike.

To accomplish this we construct a clock 50 having bells of different tone, one for the hour and one for the half hours and a ringing mechanism so arranged that the half hour bell will be sounded in the same manner as the hour bell, that is, if it is half 55 past three, the half hour bell will be sounded

three times. Under these circumstances, any one familiar with the tone of the bells will readily determine the exact time upon hearing the clock strike.

A further object of our invention is to so 30 arrange the parts and simplify the construction that the same principle may be employed with clocks for sounding the quarter hours, as well as the half hours, four bells of different tones being then used. 35

With these and other objects in view, our invention will be more fully described, illustrated in the accompanying drawings, and then specifically pointed out in the claims which are attached to and form a part of 40 this application.

In the drawings: Figure 1 is an elevational view of our invention; Fig. 2 is an end elevation partially in section of the same; Fig. 3 is a perspective view of the 45 bells and mechanism for shifting the bells alternately into the path of a common ringing hammer, showing the bells in one position; Fig. 4 is a view similar to Fig. 3, but showing the bells in another position; Fig. 5 is a top plan view of the bells employed, the hammer arm being shown in section; Fig. 6 is a perspective view similar to the 50 view shown in Figs. 3 and 4, but illustrating the type of construction employed with 55 clocks striking the quarter hours, as well as the half hours; Fig. 7 is an elevation of a modified form of wheel for controlling the 60 striking mechanism.

Corresponding and like parts are referred 65 to in the following description and indicated in all the views of the drawings by the same reference characters.

The greater part of the striking mechanism illustrated in the drawings is of conventional construction and therefore needs 70 but little description. The hour shaft 10 is provided with diametrically extending arms 11 which operate every half hour, in the usual way, to raise the latch or detent 12 and so release the main wheel 13 of the striking mechanism, all of this construction being conventional and operating in the usual manner with the exception of the main wheel 13, the novel features of which will 75 be later explained.

Vertically aligned, spaced brackets 14 and 80 15 form bearings for a vertically disposed rotatable shaft 16 provided adjacent one end with diametrically disposed arms 17 and 18 85

carrying bells 19 and 20 of different tone. This shaft 16 is provided adjacent its upper end with a radially directed pin 21 adapted to seat in one or the other of depressions 22 formed in the free end portion of a spring arm 23, the seating of the pin in either of the depressions yieldably holding the shaft against turning movement toward the other depressions.

10 Keyed upon the upper end of the shaft 16, is a cam member 24 having a pair of angularly disposed arcuate cam arms 25 and 26.

Fast upon the shaft 10 is a collar 27 provided adjacent one end with a radially directed arm 28 and adjacent its other end with an oppositely extending arm 29, these arms being disposed to engage the arms 25 and 26, respectively, of the cam member to 20 alternately turn the shaft in one direction or the other to bring the peripheral edge portion of one or the other of the bells 19 and 20 in the path of a hammer 30 carried by the spring arm 31. The collar 27 is so 25 fixed upon the shaft 10 that the arms 28 and 29 engage the cam arms to move the bells a short time before the hour and half hour because of which the bells are alternately exposed to or extended in the path of the 30 hammer. It will therefore be apparent that one of the bells will be sounded when the hour is struck and the other when the half hour is struck and inasmuch as the bells are of different tone any one hearing the clock 35 can readily determine whether the clock is striking an hour or a half hour.

In order that one may readily determine which half hour is being struck, the main wheel 13 of the striking mechanism is 40 slightly modified in its construction. In common practice wheels of this type are provided with a plurality of deep notches formed in their peripheral edges with a plurality of shallower notches interposed between the deep notches, the deep notches being arranged to seat the detent upon the sounding of the last stroke of the bell and so lock the wheel against further rotation until raised from said notch while the shallow notches determine the number of strokes given the bell. For this reason, the wheel is 45 ordinarily provided with eleven shallow notches followed by a deep notch to cause the clock to strike twelve, then followed by a second deep notch to cause the same to strike one, then by a shallow and deep notch for two, two shallow and one deep notch for three and so on.

In the construction of our main wheel 13 50 of the striking mechanism the number of notches is doubled, there being two successive series of eleven shallow notches and one deep notch permitting the clock to strike twelve twice in succession, then a deep notch 55 for one o'clock, a second deep notch for one-

thirty, a shallow and deep notch for two, a second shallow and deep notch for two-thirty, two shallow and one deep notch for three, two shallow and a deep notch for three-thirty and so on. In the drawings, 70 the deep notches are indicated by the numeral 32 and the shallow notches by the numeral 33 and the arrangement thereof will be readily understood from inspection.

From the foregoing description it will be 75 apparent that the clock will strike the hours in the usual manner upon one of the bells and that it will strike the half hours upon the other bell. It will further be apparent that the striking of the half hours will consist in sounding the second bell as many times as the hour bell was last sounded. For instance, assuming that the bell 19 is the hour bell and the bell 20 the half hour bell, at three o'clock the bell 19 would be 80 sounded three times and at three-thirty the bell 20 would be sounded three times. As these bells are of different tone however, it will be clear that any one acquainted with the clock may readily determine whether it 85 is the hour that is being sounded or the half hour and consequently the exact time.

The above described construction may be readily modified for use with striking mechanism arranged to strike the quarter hours, 90 as well as the half hours. Under such conditions there will be four equally spaced apart radially directed pins 11 instead of two and the collar 27 will be replaced by a collar 34 having four radially directed arms 100 35 as shown in Fig. 6 of the drawings. The shaft 16 will also carry four radially directed arms at its lower end each of which will form a support for a bell of different tone, the bells being indicated by the numerals 36 and 37, 38 and 39. Upon the upper end of the shaft 16 will be mounted a cam member 40 in the form of a star gear having four equally spaced apart arcuate arms 41 adapted to be engaged by the arms 110 35 of the shaft 34.

It will be seen that with this construction the shaft 16 will be turned in the same direction at all times, being advanced through ninety degrees angle every fifteen 115 minutes in order that one bell, say the bell 36, shall extend in the path of the hammer at the hour, the bell 37 at quarter after the hour, the bell 38 at half past the hour and the bell 39 at quarter of the next hour. 120 With this type of construction a main wheel 42 corresponding to the main wheel 13, but with four series of similarly arranged teeth, instead of two, will be employed, the construction of the wheel being clearly shown 125 in Fig. 7 of the drawings.

The half hour and fifteen minute ringing mechanisms illustrated in the drawings and above described disclose sufficiently the principle of my invention and it will be readily 130

apparent that by properly carrying out this principle a clock may be made to strike any desired hour divisions, each division being sounded upon a different bell, the number 5 of divisions sounded depending upon the number of sets of teeth in the controlling wheel of the striking gear and the number of bells employed, together with the mechanism for bringing the bells successively into 10 position.

The above striking mechanism is not at all complicated and is effective and positive in its action and may be readily applied to clocks now in use. It will of course be understood that we do not wish in any way to limit ourselves to the specific details of construction shown as various minor changes, within the scope of the appended claims, may be made at any time without in the 15 20 slightest degree departing from the spirit of our invention.

Having thus described the invention, what is claimed as new is:

1. A clock striking mechanism including 25 a striking hammer, means for actuating the hammer to strike the hours and fractional parts thereof, a vertically disposed shaft carrying a plurality of bells, and means for partially rotating the shaft to bring the 30 bells successively in the path of the hammer, said means including actuating arms extending radially from an hour shaft, and a cam member mounted upon the bell shaft and having arms adapted for engagement by 35 the arms of the hour shaft.

2. A clock striking mechanism including a striking hammer, means for actuating the hammer to strike the hours and fractional parts thereof, a vertically disposed shaft 40 carrying a plurality of bells, and means for partially rotating the shaft to bring the bells successively in the path of the hammer, said means including actuating arms extending radially from an hour shaft, a cam 45 member mounted upon the bell shaft and having arms adapted for engagement by the arms of the hour shaft, and means for holding the shaft with the bells in proper position.

50 3. A clock striking mechanism including a striking hammer, means for actuating the

hammer to strike the hours and fractional parts thereof, a vertically disposed shaft carrying a plurality of bells, and means for partially rotating the shaft to bring the 55 bells successively in the path of the hammer, said means including actuating arms extending radially from an hour shaft, a cam member mounted upon the bell shaft and having arms adapted for engagement by the 60 arms of the hour shaft, means for holding the shaft with the bells in proper position, said means including a pin extending radially from the shaft, and a spring arm bearing against the pin and having depressed portions in which the pin seats. 65

4. In a clock striking mechanism, a shaft, differently toned sounding elements mounted upon the shaft, cam elements carried by the shaft, one for each sounding element, 70 means actuated by the time movement for operating the cam elements to successively bring the sounding elements in predetermined position, means for retaining the sounding elements in the adjusted position, 75 a hammer, and actuating means for actuating the hammer a like number of times on the hours and at given intervals between the hours.

5. In a clock striking mechanism, a shaft, 80 differently toned sounding elements mounted upon the shaft, cam elements carried by the shaft, one for each sounding element, means mounted upon the hour shaft for operating the cam elements to successively 85 bring the sounding elements in predetermined position, means for holding the sounding elements in the adjusted position, a hammer, hammer actuating means for operating the hammer a like number of times 90 on the hours and at given intervals between the hours, and means mounted upon the hour shaft for tripping the hammer actuating means.

In testimony whereof we affix our signatures in presence of two witnesses.
